CAR COUPLER

Alfred C. Schmohl, Beaver Falls, and Halfdan N. D. Asper, Koppel, Pa., assignors, by mesne assignments, to Koppel Industrial Car and Equipment Company, McKees Rocks, Pa., a corporation of Pennsylvania

Application April 29, 1931, Serial No. 533,600

11 Claims. (Cl. 213—9)

Our invention pertains to couplers and, particularly, to that type of coupler known as the link and pin coupler, which is used chiefly in mine cars and other small cars, particularly adapted to industrial use.

An object of our invention is to provide a coupler of the link and pin type in which the link is adapted to be moved into a position within the coupler head so as to be out of the way of the entering link of the adjacent coupler being joined therewith.

Another object of our invention is to provide a coupler of the link and pin type in which the link, when moved to idle or inactive position, will be free of the coupling pin.

A further object of our invention is to provide a coupler of the link and pin type in which the link may be moved into and retained in a coupling position and moved out of coupling position into an inactive position by the operator while standing adjacent one side of the coupler and out of the way of the opposing coupler of the adjacent car as the two cars are being coupled.

Referring now to the drawings, Fig. 1 shows in plan the coupler of two adjacent cars coupled together with the link of one coupler moved to idle position and the link of the other coupler shown in pulling position; Fig. 2 is a view taken along line 2—2 of Fig. 1 showing a side elevation of one coupler and a sectional view of the other coupler; Fig. 3 is an end view of the housing shown in Fig. 10 taken along the rear face of the housing with the backing plate removed; Fig. 4 shows in elevation, the coupling link; Fig. 5 shows the rear face of the coupler in Fig. 2 taken along the lines 5—5 of Fig. 1 with the spring housing removed; Fig. 6 is an end view of the front face of the coupler shown in Fig. 2 and taken along line 6—6 of Fig. 1 with the coupling link and pin removed; Fig. 7 shows in elevation the drawhead of Fig. 2; Fig. 8 is a plan view of the drawhead of Fig. 7; Fig. 9 shows in elevation, the housing for the drawhead in Fig. 2; Fig. 10 is a plan view of the housing shown by Fig. 9.

Referring now in detail to the drawings wherein like reference characters refer to like parts, reference characters 1 and 2 indicate opposing couplers, each including drawheads 3 and housings 4. Each drawhead 3 includes buffing faces 3^a and a shank portion 3^b extending rearwardly between the buffing faces. Each housing 4 comprises a rear face and forwardly projecting spaced portions 17 between which the drawhead shank 3^b is inserted.

55 Adjacent the buffing faces 3^a of the coupler

and inwardly thereof is mounted a coupling pin within the openings 7 and 7^a. Each pin comprises a link engaging portion 9 and a handle portion 10. The handle portion 10 has an opening therein through which one end of the link engaging portion 9 is inserted. The portion 9 has its free end enlarged to prevent removal of the pin 8 from the drawhead through the opening 7. In assembling the pin the small end of the portion 9 is inserted through the opening 7^a and upwardly through the opening 7, the handle portion 10 is attached to the small end and secured therein by a transverse pin or other means. It will be observed that the opening 7^a is large enough to pass the enlarged end of the pin 8 and the opening 7 is large enough to pass the major portion of the pin, but too small to permit passage of the enlarged end, thereby preventing accidental removal of the pin 8 from the drawhead.

The shank 3^b of the drawhead has an opening 11 therein which extends from the buffing face of the drawhead through the rear wall of the drawhead shank as shown in Figs. 5 and 6 of the drawings. The side walls of the drawhead shank are provided with flanges 11^a restricting the opening 11 and the end wall 21 partially closes the rear of the opening 11 for a purpose hereinafter set forth. The bottom wall of the shank portion is depressed as at 11^b from the end wall 21 to adjacent the buffing faces 3^a for a purpose herein-after set forth.

Mounted within the opening 11 of the drawhead shank is a coupling link 12 having a slotted pin engaging portion 13 and a butt portion 14, the latter moving within the depression 11^b. This link is inserted through the opening in the end wall 21 before the drawhead is assembled with the housing 4, thereby retaining the link within the drawhead at all times and against accidental loss when the drawhead is mounted upon the car. A handle 15 may be inserted through the opening 15^a of the drawhead and secured in the butt portion 14 of the link for convenient manipulation of the link into and out of coupling position without the operator going between the cars for this purpose.

As shown by Figs. 1 and 2 of the drawings, each drawhead is provided with a coupling link 12, but one of which is active in joining the opposing couplers. The link which is not in active use is moved to idle position by rotation on its butt portion 14 so as to bring the portion 13 of the link between the flanges 11^a and the entire link moved inwardly a sufficient distance to permit entrance of the active link. It will be observed

that in this idle or inactive position, whilst the flanges 11^a are spaced apart a sufficient distance to permit the passage of the portion 13 of the link, the butt portion 14 is too large to move between the flanges, thereby preventing separation of the link and drawhead. Since the depression 11^b stops short of the outer face of the drawhead the link cannot be withdrawn from the coupler through the front thereof and when the link is in active position the pin 8 engages with the slotted portion 13 to transmit pulling forces from the link to the drawhead.

Referring now to Figs. 1, 3 and 9 of the drawings the housing 4 comprises the rear face or base having spaced forwardly projecting spring housings 17 . These latter housings are semi-circular in form having openings facing inwardly from the top and bottom edges of the housing base and are hollow, having an opening 16 extending from end to end thereof. Inwardly of the outer end of the housing 17 is a shoulder 19 and between this shoulder 19 and the outer end of the housing, the opening 16 is enlarged for a purpose hereinafter set forth.

Referring now to Figs. 4, 7, 9 and 11 of the drawings it is apparent that a coupler of this design not only provides a means for coupling two cars together but also absorbs the shocks incidental to bringing the cars together to effect coupling and the pulling strains when the cars are in motion. In assembling the draw head 3 and housing 4 , the openings 16 in the portions 17 of the housing 4 are large enough to permit the insertion of the shoulders 18 of the drawhead. The openings 16 are restricted in diameter from the shoulders 19 to the rear face of the housing 4 and contain the coiled springs 5 . At one end of the spring 5 a washer 20 spaces the spring from the shoulder 18 of the drawhead 3 and at the other end a cap 21 serves to cover the end of the spring and to provide a seat for the head of the bolt 6 .

After inserting the spring 5 within the opening 16 the washers 20 and spring caps 21 are placed at their respective ends of the spring and the bolts 6 are inserted. The shoulders 18 of the draw head are placed within the openings 16 and one end of the bolts 5 are passed through the openings 22 in the shoulders 18 . The nuts 23 are then placed on the bolt 6 and the housing and draw head are secured together. A plate 24 is placed over the entire rear face of the housing and is secured in place by machine screws 25 or other fastening means. This presents a smooth face on the rear of the coupler and permits assembling to the end of the car by means of bolts or other fastening means inserted through the openings 26 .

From the above it will be apparent that when two cars equipped with couplers of this design come together during operation of the cars, the shoulders 18 of the draw heads move inwardly of the opening 16 in the housing 4 and compress the spring 5 which takes up any shocks and prevents their being transmitted to the car underframe.

Likewise when the cars are at rest and are being put into motion, the pull of the draw head is transmitted through the bolt 6 and spring caps 21 to the springs 5 which take up the starting shocks and thus protect the car underframe.

Having thus described the invention what we claim as new and desire to secure by Letters Patent is:—

1. In a car coupler in combination, a housing, a drawhead, said housing comprising a portion for mounting upon a car body and a plurality of sup-

ports for the drawhead, said drawhead comprising a buffing face, a butt portion for the reception of the coupling link, and a plurality of lugs on said butt portion inwardly of the buffing face and adapted to engage the supports on said housing. 5

2. In a car coupler, a housing and a drawhead, a coupling link within said drawhead, a floor in said drawhead, an offset portion in said floor extending from back of the front face of the drawhead through the rear of the head, an enlarged butt on said link seated in said offset portion, said housing preventing removal of the link through the rear of said head. 10

3. In a car coupler, a housing and a drawhead, a coupling link within said drawhead, a floor in said drawhead, an offset portion in the floor extending from back of the front face of the drawhead through the rear of the head, an enlarged butt on said link seated in said offset portion, the housing preventing removal of the link through the rear of said head and openings in the sides of the drawhead and housing for the reception of the link when in idle position. 20

4. In a car coupler in combination, a housing, a drawhead movably mounted within the housing, shoulders projecting from the drawhead, shoulders within the housing adapted to engage the shoulders of the drawhead, thereby limiting the inward travel thereof, and resilient means mounted within said housing engaging the shoulders on the drawhead. 25

5. In a car coupler in combination, a housing, a drawhead movably mounted within the housing, said drawhead comprising a buffing face and a butt portion, shoulders within the housing adapted to engage the shoulders on the drawhead thereby limiting the inward travel thereof and resilient means mounted within said housing engaging the shoulders on the drawhead. 35

6. In a spring coupler of the class described, a spring housing and drawhead retaining member comprising a base having vertically spaced pairs of spring housings, each pair being joined by a horizontally disposed web to form a drawhead receiving enclosure having open sides, each housing comprising a spring enclosure and an enlarged end portion on the said enclosure to receive and support a drawhead, each end of the enclosure being closed by a suitably apertured means to receive a fastening member passing through both closing means to secure the drawhead in position. 45

7. In a spring coupler of the class described, a spring housing and drawhead retaining member comprising a base, a plurality of spring housings secured to the base and spaced to receive a drawhead between the housings, springs in said housings, means associated with the base and housings to secure the drawhead in position and apertures in the base member to receive fastening members for securing the coupler to a car body. 55

8. In a spring coupler of the class described, a drawhead comprising a horizontal bifurcated buffing face, a butt portion disposed rearwardly of the buffing face, a plurality of shoulders projecting from the drawhead intermediate the ends thereof, a chambered opening in the butt portion extending throughout the length thereof and connecting the bifurcated buffing face, said opening being restricted adjacent the said bifurcation, 65 openings in the sides of the butt portion joining with the bifurcation in the buffing face, a coupling link having an enlarged end portion and mounted in the chamber of the drawhead, said link being insertable through the rear face of said 70

5 butt portion and retained by said restriction in the chamber adjacent the buffering face, a coupling pin on the drawhead spanning the bifurcation in the buffering face and detachably engaging the coupling link, and a housing member completing the coupler having portions engaging the shoulders on the drawhead.

9. In a car coupler, in combination, a drawhead comprising a horizontally bifurcated buffering face and a butt portion having a longitudinally disposed opening therein connecting with the bifurcation in the buffering face, said opening being smallest adjacent said buffering face, restricted openings in the sides of said butt portion joining the bifurcation in the drawhead, a coupling link within the butt portion and having an enlarged end portion of a size larger than the drawhead butt side openings or end opening adjacent the buffering face, and a body portion smaller than said side opening, a coupling pin in the drawhead adjacent the buffering face and movable for selective engagement with the coupling link when in pulling position, and for disengagement therefrom to permit storage of the link within the said butt portion and projecting through said butt side openings independent of the pin, and a housing member for mounting the drawhead upon a car.

10. In a car coupler, a drawhead having a bifurcated buffering face, a coupling pin disposed rearwardly of said face and spanning the bifurcation, a butt portion on the drawhead having a

longitudinally disposed chambered opening joining the bifurcation of the buffering face and side opening forming a continuation of said bifurcation, a coupling link within the butt portion and normally adapted to project beyond the buffering face, said link when in pulling position being retained within the drawhead through engagement with the coupling pin and being adapted to be stored, in idle position, within the butt portion of the drawhead in a position transversely thereof, independently of the pin, said link having an enlarged end portion preventing removal of the link through the side openings in the butt portion when in storage position.

11. In a spring coupler, a spring housing and drawhead supporting member comprising a base provided with a plurality of spaced hollow spring housings, a drawhead provided with spaced shoulders for engagement within said spring housings, apertures in said shoulders, a compression spring within each housing and behind each drawhead shoulder, apertured spring abutment members at each end of each spring, means retaining the abutment members within the housing and a fastening member extending longitudinally of each spring and through apertures in the drawhead shoulders and abutment members to retain the drawhead and supporting member in assembled relation.
